UNITED STATES PATENT OFFICE.

THADDEUS W. BOYLE, OF AUGUSTA, GEORGIA.

SHOVEL-PLOW.

SPECIFICATION forming part of Letters Patent No. 392,308, dated November 6, 1888.

Application filed March 1, 1888. Serial No. 265,781. (No model.)

To all whom it may concern:

Be it known that I, THADDEUS W. BOYLE, a citizen of the United States of America, residing at Augusta, in the county of Richmond 5 and State of Georgia, have invented certain new and useful Improvements in Shovel-Plows, of which the following is a specification, reference being had therein to the accompanying drawings.

10 My invention relates to improvements in shovel-plow stocks in which the standard is adjustably secured to the beam; and the objects of my improvement are to provide said standard and beam with a plate of peculiar construction to embrace the bolt uniting said parts and prevent its escape and the displacement and change of relative position or the angle made by the standard with the beam. I attain these 15 objects by the construction illustrated in the accompanying drawings, in which—

Figure 1 is a perspective view of a plow-beam and standard having their connecting-bolt adjustably retained by a fluted plate constructed in accordance with my invention. 25 Fig. 2 represents in side view an ordinary fluted plate provided with a fluted cap-plate of the form shown in Fig. 1. Figs. 3, 4, 5, and 6 represent in side view modified forms of bolt-retaining plates constructed in accordance with 30 my invention.

In said drawings, A represents the beam of a plow; B, the foot to which a shovel or plow-point is generally attached; and C is the back brace having one end secured to the under side 35 of the rear end of the beam at a, and having its front end passing between the branches of the foot B, to which they are connected by means of the pivot-bolt b. The branches of the foot B are suitably bent and spread apart 40 at their upper end to receive the beam A between them, and a bolt, d, passing through the upper end of said branches and above the beam B, keeps these parts united. When a horse or team is pulling the plow and its shovel is 45 in engagement with the soil, the tendency of the bolt d is to press upon the top of the beam, and, as it is sometimes necessary or desirable to change the angle formed by the lower end of the foot or its shovel with the ground, a 50 plate provided with open-top transverse serrations or flutes (nearly similar to the lower

half, E², of Fig. 2) is secured to the top of the beam to receive the bolt d in one of its flutes.

All the above-described parts have heretofore been in use; but I found that no reliability could be placed upon an open-top fluted plate to keep the foot at a proper angle or its bolt in the flutes after the shovel is lifted off the ground. If the plowman suddenly lets fall the plow or presses upon its handles or rear end, the foot B will rotate upon its pivot b and the bolt d skip rearward over one or more of the flutes and even over the rear end of the fluted plate. To remedy this defect, I provide the beam with a closed-top bolt-retaining plate, 60 or a plate having its fluted top sufficiently closed to prevent a bolt passing therethrough from jumping out of the flutes or perforations made transversely therethrough. This plate is shown at E in Fig. 1. It is secured to the top of the beam by bolts or screws f, passing therethrough at each end and entering said beam. It has a closed top and serrations or flutes e in its under side, through one of which is passed the bolt d, that unites the upper end of the branches 70 of the foot B. This is the form of plate that I prefer, as it fulfills the requirements for which it is made; but as it may be regarded as objectionable for the bolt d to indent the upper surface of the beam under the flutes e, I 75 may also use the fluted plate E² in connection with the closed-top plate E, as shown in Fig. 2; or, if the two plates E E² are cast at the same time and in close contact, I obtain the bolt-receiving plate shown in Fig. 3 at E³, having perforations e³ for the passage of the bolt d; but to facilitate the casting of said plate with the perforations e³ therein cores may be needed, and to facilitate their retention at uniform distances apart they may be united together at the side 80 by narrow strips, which will leave openings e⁴ in the top of the plate E³; but as these openings are much narrower than the body of the bolt d to be received in the cylindrical cored openings, the top of said plate E³ will be closed 85 against the escape of the bolt from its cylindrical openings, and will fulfill the requirements of my invention.

The modification shown in Fig. 5 is preferably made of a sheet-metal strip corrugated 90 to present bolt-receiving flutes either above or under its surface. The top plate in Fig. 6 is

also made, preferably, of wrought metal, and its bolt-receiving flutes slightly larger than in Fig. 2.

Although the plate having a series of flutes or perforations is shown applied to the top of the beam, it may also be applied to the bottom of the beam to adjust the angle made by the foot B with the beam.

Having now fully described my invention, I claim—

1. The combination of a plow-beam, its foot, and transverse bolt with a plate having a series of transverse flutes or openings, and a closed top above said flutes parallel with the top of said beam and secured thereto, substantially as and for the purpose described.

2. The combination of a plow-beam, its foot, and transverse bolt with a plate having a series of transverse openings for the reception of said bolt, and a body overtopping said openings parallel with the top of said beam and secured thereto, substantially as and for the purpose described.

20

In testimony whereof I affix my signature in presence of two witnesses.

THADDEUS W. BOYLE.
